Application June 3, 1944, Serial No. 538,578

21 Claims. (Cl. 93—42)

1

This invention relates to a method and apparatus for the closing of cartons, and more particularly to a method and apparatus whereby metal fasteners are employed at the corners of the carton.

The invention herein described is, broadly speaking, a modification of the invention disclosed in my co-pending application, Serial No. 524,849, filed March 1, 1944. In the said co-pending application, there is shown and described a method wherein the corner of the carton which is to be fastened is gripped and pinched between the two jaws, and while it is so held in the jaws, a staple is driven diagonally through the corner with the bridge of the staple, when it is ultimately driven, being flat against one surface of the box, and the legs of the staple being clinched against or into the adjacent wall of the box which is perpendicular to the one against which the bridge is engaged. In other words, the staple extends diagonally across the corner with the bridge for example, engaging the top of the box, and the legs emerging through and being clinched into the vertical end wall of the box.

The present invention contemplates a similar method insofar as it involves the pinching of the corner of the box and the driving fastener, while the corner is so pinched. It is different from said application, however, in that with the present invention the staple or other fastener embraces or encircles the corner of the box as well being engaged in the corner. While either arrangement very effectively and satisfactorily closes the box, the present invention may be preferable in certain types of cartons, and also may better adapt itself to a machine in which a number of drivers spaced side by side function simultaneously. This is due to the fact that the fastener being driven, in at least some embodiments of the present invention, from a different direction than is shown in the said co-pending application, enables the stapling heads to be placed closer together. In other words, if the wire which forms the staple or other fastener feeds into the forming machine from the side, the stapling heads must be further apart, where a plurality of them are simultaneously used, than where the wire or other fastener can be fed in a direction extending fore and aft of the machine instead of sideways.

My invention may be more fully understood by reference to the accompanying drawings, in which:

Fig. 1 represents a section through the upper

2

portion of a box or carton of conventional form before the top flaps have been secured;

Fig. 2 is a similar view showing the corner after the securing means has been driven into place;

Fig. 3 is a view showing the same corner portion of a box or carton in position to be engaged by the stapling mechanism, a simple form of stapling mechanism being shown in elevation;

10 Fig. 4 is a view similar to Fig. 3 showing the portion of the parts just as the staple is about to be driven;

Fig. 5 is an elevation looking into the jaws of the machine from the under face of the jaws, the elevation being at an angle to 90° from Figs. 15 3 and 4.

Fig. 6 is a perspective view of one of the jaw elements and guide for the other jaw element, the supporting arms being omitted;

20 Fig. 7 is a transverse section in the plane of line VIII—VII of Fig. 6, the operating cam, however, being omitted;

Fig. 8 is a transverse sectional view through a modified form of machine, showing the jaws 25 in the act of pinching the corner of the box, the corner of the box being shown in section; and

Fig. 9 is a view similar to Fig. 8 at the completion of the driving of the fastener.

In the modification shown in Figs. 3 to 7, a 30 U-shaped type of staple, i. e., a staple having two legs and a bridge portion is employed, whereas in Figs. 8 and 9 the fastener is merely a flat strip of metal which is curled around in the driving operation.

35 Referring first to Figs. 1 and 2, the upper portion of a carton is illustrated. In these views, A designates the end wall of the carton which is shown in section; B designates the side wall; C designates the end flap which is folded in

40 over the top of the carton, and D designates the side flap that is folded in over the flap or lift C. Boxes of course are of various types, and the one illustrated is a conventional one. Normally there are two flaps D which fold inwardly 45 from the sides, and which either meet on the center line of the box, or, preferably, overlap to increase the strength of the carton.

Referring to Fig. 2, the corner portion of the box has been distorted or pinched together and 50 a staple S embraces this corner portion of the box, the legs of the staple being curled around the corner, the ends of the legs penetrating the material as indicated at S', and being lapped inside the material of the corner.

55 In the drawings, Figs. 3 to 7 inclusive, a very

simple mechanism reduced to its basic elements is illustrated, the mechanism illustrated, however, operating according to the present method. The machine illustrated in Figs. 3 to 7 has two guide arms 2 and 3, conveniently formed of angle irons, and which are welded to a connecting plate 4, (which plate is best shown in Figs. 5 and 6, but in the latter view the arms 2 and 3 are not shown). As shown in Figs. 3 and 4, the two guide arms 2 and 3 are set over the corner of the box, the arm 2 resting on the top of the box in the particular assembly illustrated, and the arm 3 extending down against the end wall A. The connecting plate 4 has a notch 4a on the inner edge thereof, so that the corner of the box can be received in the stapling mechanism as clearly shown in Fig. 3.

The face of the connecting plate 4 opposite the one to which the angle arms 2 and 3 are welded is provided with a longitudinally extending guideway or channel 5 (see Fig. 6). Two jaw elements 7 and 8 set on the guide plate 5 and have extensions 7' and 8' respectively which fit in and slide along the guideway 5. Additionally the connecting plate 4 is provided with two spaced longitudinally extending slots 4'. As best shown in Fig. 7, screws 9 pass through these slots into the respective blocks 7 and 8 and the screws are provided with flanged ferrules 10 which fit in the slots 4'. This arrangement secures the jaw elements 7 and 8 to the connecting plate 4 while permitting them to slide toward and away from each other.

The opposed faces of the blocks or jaws 7 and 8 are provided with protruding lips 11 along one edge thereof. These protruding lips are best seen in Figs. 3 and 4. Inwardly from the protruding lips are rounded surfaces or grooves 12. Extending transversely of the lips 11, from the outer surface of each block 7 to the groove 12, is a staple guiding groove 13.

Passing through the blocks or jaws 7 and 8 are holes 14. A connecting link 15 passes through the holes in the two jaws, and surrounding this link in between the two jaws is a compression spring 16. One end of the link is threaded and carries nuts 17 thereon. The other end of the link is provided with an eye 18 which is engaged by a pin 19, this pin also forming a fulcrum for an eccentric cam 20. The cam 20, best shown in Fig. 5, is a bifurcated cam with the eye extending between the two plates or cheeks of the cam. The cam is provided with an operating handle 21.

The arrangement is such that when the cam is in the position shown in Fig. 3 the two jaws 7 and 8 will be held apart by the compression spring 16. However, when the cam is rotated to the position shown in Fig. 4, the two jaws will be caused to move toward each other. It will be noted that in this assembly both jaws move relative to the base plate 4, the jaw 7 being pulled toward the jaw 8 by the connecting link 15 and the jaw 8 being moved toward the jaw 7 and by pressure exerted by the cam. When the machine is applied to the corner of a box as illustrated in Figs. 3 and 4, the movement of the two jaws in the manner described serves to pinch and gather the corner of the box into a compressed seam or fold.

While the parts are held in the position shown in Fig. 4, a U-shaped staple S is dropped into the top of the staple guide formed by the opposed grooves 13, and a driver 22 having rabbeted edges 23 is entered between the two jaws with the said edges engaging in the guideway. The lower end

of the driver is concave, conforming to the arch shape of the bridge of the staple S. The parts are then in the position shown in Fig. 4. The driver 22 is then moved with a blow in the direction of the arrow shown in Fig. 4. The two legs of the staple, which at this time straddle the gathered or beaded edge portion of the box, move down into contact with the lips 11. These lips deflect the ends of the staple legs inwardly toward each other, acting as anvils to start the clinching of the staple before the legs of the staple actually enter the material of the box. The shaping of the legs of the staple initiated by the lips 11 is governed by the shape of the lips and their relative levels and continues as the staple is driven. The legs of the staple are shown as eventuallylapping each other in the material forming the corner of the box. When the staple has been completely driven, the rounded bridge will embrace the beaded or gathered in portion of the box, the legs will overlap in this portion, forming a substantially closed loop or ring. By changing the shape of the lips 11 a greater degree of curvature in the legs may be produced. The gathered or pinched in portion of the box is straddled by the staple as it is driven, forming a mandrel to support the legs of the staple and in conjunction with the lips 11 cause the legs to be deflected inwardly through the corner of the carton.

Upon completion of the driving of the staple, the driver is removed, the cam 20 returned to the position shown in Fig. 3, and the jaws open. The implement may then be moved along the box or engaged against another box, and the cycle repeated. It will be noted that in this operation the fastener engages the corner of the box in such way that one leg or end of the fastener enters the gathered or pinched in portion from the top surface corner, and the other enters the corner from the end surface A.

In the modification shown in Figs. 8 and 9, there is a lower jaw member 25 and an upper jaw member 26. These jaws are indicated as being provided with operating extensions 25a and 26a respectively. These extensions may be moved by an appropriate mechanism not shown, but the arrangement is preferably such that movement is imparted to both jaws simultaneously. The lower jaw 25 is in the form of a block of metal having a recess in the under face thereof extending from the upper end of the block downwardly to a point intermediate the two ends of the block, this recess terminating in a rounded surface 25b which has a lip portion 25c.

The upper jaw which slides under the lower jaw has a channel in its upper face to slideably receive and guide a driver element 27. The jaw member 26 supports a magazine 28 adapted to hold a plurality of fasteners F, these fasteners being in the form of thin sheet metal. The fasteners are fed through an opening 29 in the jaw member and the channel in 25 for the driver 27 is undercut so that only a single fastener may be projected into the path of the driver at a time. This general type of construction is well known to those skilled in the art. The upper jaw 26 tapers at its lower end to form a thin lip 26c for cooperation with the lip 25c. The upper jaw 26 slides along the recessed face of the lower jaw 25 while the driver 27 works in the recess in the jaw 25 and in the channel formed in the jaw 26, being slideable relative to both jaws.

In the lower jaw member 25 is a chamber 30 in the bottom of which is a keeper member 31. This keeper member 31 has lugs 31a at each end there-

of that engage flanges at the bottom of the chamber 30 while the keeper itself projects through an opening in the bottom of the chamber. Compression springs 32 bear against the keeper for resiliently urging the keeper toward the face of the upper jaw member 26. The keeper 31 has inclined faces as clearly shown in the drawings, the arrangement being such that when the driver 27 is in the retracted position shown in Fig. 8, the keeper will bear against a fastener moving down the guideway on the face of the lower jaw 26 in advance of the driver. When the driver engages the keeper, it will cam the keeper back into the chamber 30, as shown in Fig. 9, thus allowing the driver to ride past the keeper. The keeper retards the free movement of the fastener ahead of the driver so that the driver must push the fastener ahead of it.

In operation, the corner of a box is fed between the two jaws when the two jaws are open, i. e., when the lips 25c and 26c are spread apart. In the first operation of the machine, the two jaws then move together, being operated through the operating extensions 25a and 26a respectively, pinching or bunching the corner of the box where it is engaged between the two jaws. Fig. 8 shows the parts in the position which they then occupy. The driver 27 in its stroke moves above the opening 29 so that the row of staples F can be pushed to the left as viewed in Fig. 8, advancing a single one of the fasteners into the path of the driver. The driver then descends to the position shown in Fig. 8, sliding the fastener in front of it toward the reduced end of the jaw. As the driver continues to move down, it forces the keeper 31 back and forces the lower end of the fastener through the corner of the box. The lower end of the fastener, after passing through the corner of the box, strikes the curved surface 25b, causing it to curl around. As the driving operation continues, the end of the fastener which has been curled around the corner of the box meets the rounded end surface 21a of the driver, and it is thereby clinched over to form a ring which encircles the corner of the box with the box corner being pinched together and the fastener passing diagonally through the corner of the box. In its finished form, the fastener substantially encircles the corner and also passes through the corner.

In both machines herein described, the apparatus involves a pair of jaw elements to pinch and bunch up or "gather" the corner of a box, and with each a fastener is applied in such manner that the intermediate portion of the fastener embraces the exterior of the corner while the legs are deflected toward each other, forming a circular or nearly circular binding about the corner. In each the fastener is diagonally engaged in the corner which it also encircles. The staple or fastener, constituting a closed loop or ring, may allow relative flexing between the top and end walls, i. e., a movement comparable to the turning of a page of a book (but of course of much less magnitude) there being a natural hinge action between the lifts or wall of the carton and the bunched in corner. This produces a condition tending to prevent the tearing out of the staples.

In the form shown in Figs. 3 to 7 inclusive, the anvils for deflecting the fastener are the protruding lips on the jaws, and in Figs. 8 and 9 one anvil element is carried integrally on the face of the jaw and the other anvil element is on the end of the driver, which in turn is slideably carried on the opposite jaw.

The machine, while primarily applicable to

closing cartons, may be adapted for other uses, and is adaptable, as will be understood by those skilled in the art to hand or power operation, and to machines using preformed fasteners or machines which shape the fasteners from continuous stock.

While I have shown and described certain embodiments of my invention and the method of practicing the same, it should be borne in mind that the elements of the apparatus have been reduced to an extremely simple form and that various changes and modifications are contemplated, and the method and apparatus are not restricted to the specific embodiments herein shown.

I claim:

1. Apparatus for setting fasteners comprising a pair of opposed jaw members adapted to engage and squeeze intersecting portions of the object to be fastened into a gather, and means for shaping a fastener around and through said gather.
2. Apparatus for closing a carton by the use of fasteners in the corners thereof comprising means for pinching the corner of the carton diagonally across the corner until the intersecting wall portions at the corner are brought substantially into parallelism, and means for driving a fastener into the corner while it is so pinched and shaping it about the said corner.
3. Apparatus for closing a carton by the use of fasteners in the corners thereof comprising a pair of jaw members supported for movement toward and away from each other, means for supporting the carton so that the corner thereof projects between the jaws, the jaws having a range of movement such as to squeeze the corner portions of the intersecting walls so engaged together, said jaw members having jaw portions thereon for pinching the corner of a carton, and means associated with the jaw members for driving a fastener into the corner of the box when it is engaged between said jaws and shaping the fastener about the corner.
4. Apparatus for setting fasteners in box corners comprising a pair of jaws movable toward and away from each other, means for operating the jaws, each of the jaws having lip portions of reduced thickness on the opposed faces thereof for bunching or pinching the corner of a box engaged therebetween, and a driver slideably guided between the two jaws, the range of movement of the jaws being such that the lip portions will travel inwardly past the plane of the walls constituting the box corner and push said walls inwardly against each other.
5. Apparatus for setting fasteners in box corners comprising a pair of jaws movable toward and away from each other, means for operating the jaws, each of the jaws having lip portions of reduced thickness on the opposed faces thereof for bunching or pinching the corner of a box engaged therebetween, and a driver slideably guided between the two jaws, the driver being movable in a direction perpendicular to the lips.
6. Apparatus for setting fasteners in box corners comprising a pair of jaws movable toward and away from each other, means for operating the jaws, each of the jaws having lip portions of reduced thickness on the opposed faces thereof for bunching or pinching the corner of a box engaged therebetween, and a driver slideably guided between the two jaws, the driver being movable in a direction perpendicular to the lips, the jaws having a fastener guide between the op-

posed faces thereof at right angles to and terminating outwardly, in reference to the box, of said lips so that the legs of the fastener engage the lips and are deflected thereby.

7. Apparatus for setting fasteners comprising a pair of jaw members movable toward and away from each other, means for operating the jaws, said jaws having lip portions of reduced thickness thereon for engaging the work into which the fastener is to be driven, means including a driver for driving a fastener into the work which is pinched between the jaws and shaping the fastener about the portion which is confined between the jaws, the reduced lip portions of at least one of the jaws serving as an anvil to shape the fastener, the two lips serving to concentrate the squeezing pressure of the jaws adjacent the region where the fastener penetrates.

8. Apparatus for setting fasteners in the corner of a box comprising a pair of jaws movable toward and away from each other, means for operating the jaws, the jaws having lip portions of reduced thickness on the opposed faces thereof for pinching the corner portion of a box inwardly from the corner edge, the jaws providing clearance for the corner of the box between the said jaws and the corner edge, and means for setting a fastener in the corner with the fastener encircling the corner.

9. Apparatus for setting fasteners comprising a pair of jaws movable toward and away from each other, means for operating the jaws, the jaws having lip portions for pinching the work piece adjacent the point where the fastener is to be driven, means on one of the jaws providing a staple guide, and a driver movable in said guide along one of the jaws in a direction parallel to the direction in which the jaws move.

10. Apparatus for setting U-shaped fasteners in the corner of a box comprising a pair of jaw members movable toward and away from each other, each jaw member having a box-engaging lip portion thereon, means for driving a fastener into the box corner movable in a direction perpendicular to the direction in which the jaws move, the said lip portions providing anvils for deflecting the legs of the fastener into the corner of the box while the bridge of the fastener embraces the corner of the box, and means separate from the driver for operating said jaws, whereby the corner of the box may be squeezed together by said jaws before the fastener is driven.

11. Apparatus of the class described comprising a pair of movable jaw elements, means for supporting the jaw elements diagonally across the corner formed by intersecting faces of the work piece to be operated upon to enable said jaw elements to engage and hold the corner of the work piece, and means operating between the jaw elements for driving a staple into the work piece, means for deflecting the legs of a staple into the portion of the work piece engaged between the jaw elements, and means separate from the driver for operating said jaws, whereby the corner of the box may be squeezed together by said jaws before the fastener is driven.

12. Apparatus for setting fasteners having a bridge portion and two leg portions comprising a pair of jaws, means for moving the jaws toward and away from each other, said jaws being relatively movable toward each other to grip and hold the portion of a work piece therebetween into which the staple is to be driven, means operating between the jaws and perpendicularly to their plane of movement for driving a fastener

into the work piece when it is engaged between the jaws and means separate from the driver for operating said jaws, whereby the corner of the box may be squeezed together by said jaws before the fastener is driven, the jaws having anvil portions thereon for deflecting the legs of the staple before they enter the work piece.

13. The method of closing cartons which comprises squeezing a corner formed by intersecting faces of the carton to confine the walls and bring them together inwardly of the original corner and applying a fastener to the corner while it is squeezed and shaping the fastener about the corner.

14. The method of closing cartons which comprises pinching the corner which is to be secured to form a gather, and applying fastening means to the portion so pinched with the fastening means substantially encircling the corner.

15. The method of closing a carton along the corner thereof which comprises squeezing said corner of the box diagonally across the corner until the portions so squeezed are pressed into contact with each other and applying a fastener to the portion which is thus squeezed with the mid portion of the fastener embracing the corner and with a portion of the fastener passing through the corner.

16. The method of closing a carton along the corner thereof which comprises squeezing said corner of the box diagonally across the corner until the portions of the corner so squeezed are pressed together into contact with each other and applying a fastener to the portion which is thus squeezed with the mid portion of the fastener embracing the corner and the ends of the fastener passing through the substance of the box and being brought together so that the fastener will substantially encircle the squeezed corner portion of the box.

17. The method of closing a carton along the corner thereof which comprises squeezing together a portion of the corner of the carton inwardly from the corner, engaging said corner with a fastener having a bridge portion and two legs in such manner that the legs straddle the squeezed portion of the corner of the carton, and then forcing the legs of the staple into the substance of the box in a direction diagonally of the corner.

18. The method of closing a carton along a corner thereof which comprises first squeezing the corner of the carton to bring the intersecting walls of the carton together at the corner moving a U-shaped staple toward the corner in a direction substantially perpendicular to a diagonal plane passing through the corner and progressively deflecting the legs of the staple as it is being thus driven diagonally into the corner and forcing the bridge of the staple against the exterior of the corner.

19. The method of closing cartons or the like which comprises squeezing the corner in a direction extending diagonally of the corner until the intersecting walls constituting the corner are pinched together, setting a staple astraddle of the squeezed portion of the corner, progressively deflecting the legs of the staple in a direction diagonally of the corner into the substance of the carton in the final driving of the staple.

20. Apparatus for driving staples comprising staple guiding means set astraddle the work, means for gathering a portion of the work piece into a compressed bunch, means for driving a staple

in the guiding means, the compressed bunch portion of work projecting between and serving as a means to support the inner faces of the legs, and anvil elements transverse to the direction of travel of the staple along said guide for deflecting the legs of the staple laterally into the work, the compressed bunch of paper acting with the anvil elements to confine the legs of the staple so that they are deflected inwardly across the work which is engaged between the jaws.

21. The method of driving staples into a work piece which comprises squeezing portions of the work piece into a gather to provide a firm compacted protuberance, applying a driving force to a staple with the staple over the work piece and astraddle of the protuberances so formed, and progressively deflecting the legs of the staple transversely to the direction of the driving force on the staple into the work with the legs of the staple so deflected then moving toward each other.
